METHOD AND APPARATUS FOR REGULATING THE HEAD AND CAPACITY OF CENTRIFUGAL PUMPS

Lewis F. Moody, Princeton, N. J.

Application December 19, 1942, Serial No. 469,504

15 Claims. (Cl. 103—97)

This invention relates to centrifugal pumps and compressors and more specifically to a method and construction of pump for regulating the head and capacity of such machines.

While the invention is particularly adaptable for use in high pressure multi-stage pumps, such as boiler feed pumps, it may be employed in any type of centrifugal pump or compressor without departing from the spirit of the present invention. The word "pump" as used herein includes generically the pumping of gases or vapors as well as liquids. Many types of pumps and compressors are required at times to operate at reduced capacity and this commonly entails impaired performance. For example, at normal operating capacity, a boiler feed pump must overcome the boiler pressure plus the resistance in pipe lines and feed water heaters in the system between the pump and boiler, which resistance may be between ten and twenty percent of the boiler pressure depending on the length of the pipe lines and the number and type of feed water heaters so employed. When operating at a reduced capacity, a multi-stage centrifugal pump of usual type produces more pressure than when operating at a normal capacity while the frictional losses in the piping and feed water heaters fall off sharply at reduced capacities. Consequently at reduced capacity operation, the pump produces considerably more pressure than is required for feeding the boiler.

It has heretofore been the accepted practice, when employing a constant speed prime mover for the pump, to throttle such excess pressure by a boiler regulation valve which throttles the entire pump discharge, thus resulting in an appreciable loss of power and energy; and the high velocity thus created necessitates valves constructed of special metals to withstand the erosive effects of the liquid flow, and such valves are expensive in first cost and upkeep. For these reasons various attempts have been made to regulate boiler feeding by other means than throttling, such for instance as the use of variable speed electric motors for driving or operating the pump. Variable speed electric motors are also expensive and are not available in all sizes required. The use in connection with electrically driven pumps of hydraulic couplings which permit a reduction of speed of the pump at constant speed of the motor, involves a power loss proportionate to the reduction of speed as well as a high cost of the coupling. Similar considerations enter into other pump and compressor systems,

in which a pump is desired having regulating means within itself.

It is an object of the present invention to effect the desired regulation of head and capacity of a multi-stage centrifugal pump or compressor in a comparatively simple and inexpensive manner and with a minimum waste of power, and without impairing the mechanical reliability of the machine.

More specifically the present invention effects the desired control or regulation of head and capacity of a multi-stage high pressure centrifugal pump by the by-passing of part of the liquid flow within the pump itself; i. e., by providing a passage extending from the discharge side of one impeller to the inlet passage in front of the inlet of the same impeller effecting a partial short circuit of that particular stage of the pump and effecting a reduction of the discharge capacity of the pump corresponding to the quantity of liquid by-passed.

Another object of the present invention is to provide a structure whereby the by-passed or returning stream of fluid will be introduced in a nearly tangential direction pointing in the direction of the impeller motion and discharging into a vane-free whirlpool chamber, permitting or setting up rotation of the liquid on the suction side of the impeller around which the returned liquid is by-passed. In this way the moment of momentum of the returning stream is introduced into the suction side of the impeller thereby returning to the impeller some of the work which the impeller has imparted to the liquid, with a corresponding saving in power. At the same time this action reduces the head produced by the impeller in direct relation to the moment of momentum introduced into the suction side of the impeller by the returning stream, because the head produced by a pump impeller is proportional to the difference in moment of momentum between its suction and discharge sides.

With these and other objects in view, as may appear from the accompanying specification, the invention consists of various features of construction and combination of parts, which will be first disclosed in connection with the accompanying drawings, showing a centrifugal pump of the preferred form embodying the invention, and the features forming the invention will be specifically pointed out in the claims.

In the drawings

Figure 1 is a longitudinal section through a multi-stage centrifugal pump constructed in accordance with the present invention.

Figure 1A is a developed fragmentary longitudinal section somewhat distorted for the purpose of clearly illustrating the by-pass.

Figure 2 is a cross-section through the pump taken on the line 2—2 of Figure 1.

Figure 3 is a developed section taken on the line A—A of Figure 2 illustrating the flow passage and the whirl removing vanes therein.

Figure 4 is a cross-section through the pump taken on the line 4—4 of Figure 1.

Figure 5 is a fragmentary sectional view in cross-section and similar to Figure 2 differing therefrom in that it shows in section a modified construction of the means for actuating the regulating valve.

Figure 6 is a sectional view through a further modified form of the valve mechanism for controlling the by-passing of the liquid in the pump.

Figure 7 is a fragmentary longitudinal section through a modified construction of the pump structure.

Figure 8 is a detailed cross-section taken on the line 8—8 of Figure 7.

Figure 9 is a detailed cross-section taken on the line 9—9 of Figure 7.

Figure 10 is a diagrammatic, semi-perspective view, partly in phantom illustrating the improved method of regulating the head and capacity of a centrifugal pump, blower or analogous mechanism.

Referring more particularly to the drawings, a multi-stage centrifugal pump is illustrated which embodies a casing 1 having an impeller assembly therein arranged in any approved manner of stage arrangement, and with any desired number of stages, illustrated by four similarly disposed stages. The inlet for liquid to be pumped is through the suction or inlet 2 of the casing into the suction eye 3 of the first stage impeller 4 and the flow through the pump is from the first stage impeller 4 through the intermediate impellers to the final or discharge impeller 5 and thence out through the discharge passage 6.

In pumps handling water or other liquid, the capacity and head regulating features of the present invention are applied to one or more of the impellers subsequent to or following the suction or first stage impeller and preferably it is employed in one or more final stages of the pump. This arrangement is employed so that the pressure of the preceding stage or stages will supply sufficient positive suction head to prevent cavitation in the inlet or vane passages of the by-passed impeller. If applied to the first or suction stage, the high velocity and low pressure in the interior of the vortex in the inlet passage would result in cavitation, unless the pump receives the liquid under unusually high positive pressure, as from a booster pump or high elevation sump.

In a compressor or a pump for compressible fluids, this limitation is unnecessary and this by-pass control can be applied to any stage of a multi-stage compressor, or to a single-stage compressor.

In Figure 1 of the drawings, the by-passing arrangement is illustrated as applied to the final stage and preceding impellers 5 and 8.

The pump structure provides that the impeller 10 preceding the by-passed stages, discharges into a discharge volute 9 which in turn discharges into the suction of the succeeding stage impeller 8. The impeller or impellers provided with the capacity and head regulating arrangement have annular vane-free inlet passages into which the flow from the preceding impeller enters, as illustrated

by inlet passage 11 leading to impeller 8 in Figure 1 of the drawings. The volute 9 of the preceding impeller 10 discharges into the annular vane-free inlet passage 11 of impeller 8, and volute 13 similarly discharges into the vane-free inlet passage 11 of impeller 5.

Figure 3 of the drawings illustrates a developed view showing this arrangement wherein the fluid passes from the discharge volute 9 into the annular vane-free inlet passage 11 and for the purpose of straightening out and removing pre-whirl from the fluid flowing from volute 9 into the passage 11 a plurality of relatively short stationary curved vanes 12 are provided at the entrance into the annular vane-free suction passage 11.

When a modified head-capacity curve is desired, these vanes can be formed to impart a small whirl, either positive or negative, to the normal flow.

The pump shown in the present drawings has a double discharge volute for each stage as clearly shown in Figure 4 of the drawings, and the impeller 8 rotating clockwise discharges into these volutes with a flow in the direction of the arrows indicated in Figure 4 of the drawings. The inlet ends of the volutes are diametrically opposed on opposite sides of the axis of the pump.

The casing 1 is provided with by-passes 14 one communicating with each of the dual discharge volutes 13 of the impeller 8 and since both of these by-passes and their companion mechanism are similar in construction, only one of them will be specifically described. The by-pass 14 contained within the wall of the pump casing 1 has its entrance preferably opening tangentially into the discharge volute 13 and conforming with the direction of flow in the volute and conserving its velocity head. Its discharge end leads into a longitudinal passage parallel to the pump axis, which in turn communicates with a passage leading inwardly and discharging nearly tangentially into the annular vane free inlet passage 11 of the impeller 8; i.e., the by-pass extends through the casing 1 from the discharge side of the impeller 8 back to its suction side so that a part of the fluid pumped by the impeller 8 may be returned to its suction for re-passage through the impeller. The by-pass enters passage 11 in a nearly tangential direction through the outlet nozzle 16 forming the seat of valve 15 in Figure 2.

Means are provided for regulating the quantity of discharge by-passed back to the suction of the impeller and in Figure 2 of the drawings this structure includes a needle valve 15 which is adapted to seat upon a valve seat 16 arranged in the by-pass. The valve is of a form to produce a non-turbulent cylindrical jet with little loss of head at any degree of opening. The valve stem 17 extends out of the pump casing 1 and may have hand wheel or handle 18 thereon to provide manual adjustment of the valve. The valve is located outside of the pump passages so that when closed it does not disturb the normal flow, and is readily accessible and removable from outside the pump casing for renewal or repair. Thus no mechanism is placed within the interior portion of the pump where a failure to operate would impair the reliability of the ordinary pump operation.

The by-pass passage opens nearly tangentially into the annular vane-free inlet passage of the impeller 8 pointing in the direction of rotation of the impeller thus creating a rotation of the liquid on the suction side of the impeller 8. In this way the moment of momentum of the returning stream of liquid is introduced into the suction side of the impeller 8 thereby returning some of the work

which this impeller has imparted to the liquid flow with a corresponding reduction in torque and saving in power. At the same time this by-passing of part of the discharge liquid flowing back to the suction of the impeller reduces the head produced by this particular impeller in direct relation to the difference in moment of momentum between its suction and discharge side. The by-passing of this liquid therefore reduces the head of that particular stage of the pump in two ways, i. e., first, by abstracting some of the energy of the discharge while maintaining a fairly high liquid flow through the impeller so that the impeller does not work far below its normal capacity, and secondly, by introducing a rotation on the suction side of the impeller in the direction of the impeller rotation so that the difference in moment of momentum, and thereby the head produced by the impeller, are materially reduced. The needle valve 15 being arranged so that the jet of liquid passing through the by-pass will be introduced in a substantially tangential direction with respect to the pump axis, contributing its momentum to the normally whirl-free liquid in the vane-free annular inlet passage 11, will induce or set up rotation in the liquid in the annular vane-free passage 11 in the same direction as the rotation of the pump. A vortex is thus formed in the suction passage 11 the velocity of which increases inversely as the distance from the axis, so that as the suction flow enters the particular impeller bypassed it will have a material increase of pre-rotation in the same direction as the rotation of the impeller.

The annular inlet passage 11, being vane-free comprises a passage of revolution about the pump axis of considerable radial extent, and the by-pass enters it at or near its outer periphery at a radial distance from the pump axis which as here shown is greater than the largest radius of the impeller. The main flow of liquid into the impeller also is introduced near the periphery of the vane-free annular inlet passage 11, as clearly shown in Figure 2 of the drawings, and it enters the inlet passage 11 through the direction vanes 12 which give the main flow of fluid a substantially axial or non-whirling direction, so that when the by-pass valve 15 is closed the flow will enter the impeller 8 in the normal manner without pre-whirl.

In certain instances it may be desirable to provide limited positive or negative pre-whirl to the normal main fluid flow entering the vane-free inlet passage 11 and such pre-whirl may be provided in varied predetermined degree by variance of the curvature of the direction vanes 12, to meet the requirements of the particular pump or condition to be met.

As heretofore described, when the by-pass valve 15 is open, the by-passed liquid flow will impart momentum to the body of liquid advancing normally through the pump by way of the annular inlet passage 11 and impart rotation thereto. This as previously explained has two effects on the pump performance, first, the abstraction of a part of the pump discharge through the by-passing action, thus reducing the pump capacity, and secondly, the reduction of the head produced in the stage by-passed. These two effects react on each other in such a way as to intensify their cooperative action. Since the momentum imparted to the flow entering the by-passed impeller tends to reduce the driving torque on the impeller, the load on the prime mover of the pump will be lightened or reduced, and the pump effi-

ciency will be only slightly impaired, or to a much less extent than is the case where throttling control of the entire discharge of the pump is employed by means of valves in the discharge line.

5 By employing two or more by-pass passages with their valves, in each stage of the pump by-passed, in conjunction with a twin volute discharge diffuser, symmetry about the pump axis may be preserved avoiding side thrust in the impeller, although it is to be understood that the invention is not to be limited to the employment of a plurality of by-passes since effective reduction of the head and capacity of a centrifugal pump may be provided by the use of a single by-pass per stage.

15 As is preferable, the drawings show the application of the by-pass structure to the higher stages of a multi-stage pump handling water or other liquid subject to vaporization. It is omitted from the first one or two stages of the pump, as previously explained, for the reason that the resultant velocity in the suction space is considerably increased when the by-passes are open, and such increase in velocity would with usual values of suction pressure or lift produce cavitation if applied to the first or suction stage of the pump and sometimes even in the second stage. But in utilizing the by-pass arrangement only in the higher stages of the pump a sufficient absolute pressure is developed in the preceding stages to eliminate cavitation. The exact position of the number of stages by-passed to those which are free from by-passing will, of course, depend upon the particular conditions of installation of the pump.

35 In the modified form shown in Figure 5 the pump structure is the same as in the preferred form shown in Figures 1 to 4 inclusive comprising the casing 1' having the by-pass 14' therein which is constructed the same as the by-pass 14, the only difference in this modified form being in the manner of operation of valve 15' which allows the by-pass flow of liquid into the annular vane-free suction passage 11'. In this modified form the valve stem 11' has a piston 20 mounted on its outer end. The piston 20 is mounted for reciprocation in a cylinder 21, and this cylinder has pipes 22 and 23 communicating with its opposite ends which pipes may be connected to a suitable source of supply of pressure fluid, or to the fluid supplied by the pump itself when suitable, through a three-way valve of any approved construction, so that when pressure fluid is admitted to one end of the cylinder 21 to move the valve 15' in one direction it will be allowed to exhaust from the other end of the cylinder.

55 Figure 6 of the drawings shows a still further modified construction of mechanism for operating the by-pass control valve, and in this construction the stem 25 of the valve 26 has its outer end threaded as shown at 27 and extending through the threaded bore 28 of a worm gear 29. The worm gear 29 is rotated by worm 30 which is in turn operated by an electric motor 31. The switch 32 which controls the energizing of the motor 31 is of any approved type of switch which may be purchased upon the open market and will control the direction of rotation of the motor 31. The switch 32 may be operated by pressure actuated mechanism 33 such as the piston and cylinder structure 20 and 21 shown in Figure 5. Either the structure shown in Figure 5 or Figure 6 may be utilized to provide automatic operation of the needle valves to provide automatic control of the by-pass. These controls when desired can be made responsive to head-

quantity of flow, or to the fluid level in a receiver. Any control usually applied to a throttle valve in the main flow can be applied to the by-pass control of this invention, with a gain in economy of operation and reduction of throttle valve erosion. The pressure responsive mechanism 33 of Figure 6 or the piston and cylinder arrangement 20 and 21 of Figure 5 would be operated or governed by a pressure responsive device of any suitable construction such as a Sylphon bellows or diaphragm, and since these devices and their manner of connection are well known and may be purchased upon the open market the illustration of the present application and its description have not been unnecessarily burdened by illustration and description of the devices and arrangements in detail.

Figures 7 to 9 inclusive show a modified construction of the by-pass. In this form the by-pass extends exteriorly of the pump casing. The pump casing 40 has a stage impeller unit 41 thereof, the discharge of which passes through the discharge volute 42 and thence into the suction passage of the succeeding stage. This passage has direction vanes 43 therein which correspond to the vanes 12, to take the rotation out of the normal flow of fluid as it enters the suction of the succeeding stage. The impeller unit 41 has an annular vane-free suction passage 44 corresponding to the vane-free suction passage 11.

A by-pass 45 communicates with the discharge volute 42 of the impeller 41 and extends outwardly through the pump casing 40 being connected by means of a substantially U shaped pipe connection 46 with the second leg or passage 47 of the by-pass which opens out into the annular vane-free suction passage 44. Passages 45 and 47 are shown as being both in the plane of Figure 7, but they can when desired be angularly displaced from each other about the pump axis. A nipple 48 is inserted in the discharge end of the outlet leg 47 of the by-pass and this nipple is curved as clearly shown in Figure 8 so that it will discharge the by-passed fluid into the annular vane-free inlet passage 44 in a direction nearly tangential to the axis of rotation of the impeller thus setting up rotation in the liquid in the passage 44 in the same manner as heretofore described in connection with the preferred form of the invention. A valve of any approved type, operated by a handle 49 may be placed in the U coupling 46 for controlling the flow of liquid through the by-pass back to the suction of the impeller 41 from its discharge. This modification somewhat simplifies the internal construction of the pump and makes the by-pass valve still more accessible for repair, but is less favorable than the preferred arrangement in the hydraulic conditions and control of the by-passed flow.

Since slight amounts of opening of the by-pass passages will have but little effect on the pump efficiency, a pump constructed as herein described will have a further advantage, besides those set out above, being capable of adjustment of head and capacity to suit the exact conditions desired and required by a particular installation, i. e., it sometimes occurs that the head and capacity for which a pump has been ordered are not found to be in exact agreement with the actual conditions encountered in the installation. In such instances with the pump constructed as herein described it will be possible to set the by-pass valves at any desired degree of opening, in order to give the exact head capacity values re-

quired by the operating conditions, even when these valves are not thereafter utilized for regulation. This mode of adjustment for example may be used to correct difficulties in parallel operation of pumps where a surge between the pump units is found to exist.

It will be understood that the invention is not to be limited to the specific construction or arrangement of parts shown, but that they may be widely modified within the invention defined by the claims.

What is claimed is:

1. The method of regulating the head and capacity of a multi-stage centrifugal pump which consists in returning a controllable quantity of the liquid discharged by one of the impellers to the suction of the same impeller and introducing the stream of such returned liquid into the liquid flowing to the impeller suction in a vane free chamber at a large radial distance from the axis compared with the impeller radius and passing the returned liquid radially inward through the vane-free chamber in such manner as to set up a vortex in the liquid entering the suction of the impeller the velocity of which vortex increases inversely as the distance from the axis and thereby imparts rotation to the fluid prior to its entrance into the impeller in the same direction as the rotation of the impeller.
2. In a centrifugal pump, a casing, an impeller in said casing having an inlet and a discharge, said casing provided with a vane-free inlet passage formed as a space of revolution opening into the impeller inlet, said casing having a by-pass therein the inlet of which opens into the impeller discharge and the outlet of which opens tangentially into said inlet passage, at its outer periphery the outlet of said by-pass pointing in the direction of rotation of the impeller whereby liquid entering the inlet passage from the by-pass will set up a vortex in the liquid as it passes inwardly through the vane-free passage to the suction of the impeller said vortex rotating in the direction of rotation of the impeller and increasing in velocity inversely as the distance from the axis thereby imparting rotation to the fluid prior to its entrance into the impeller in the same direction as the rotation of the impeller.
3. In a centrifugal pump, a casing, an impeller in said casing having an inlet and a discharge, said casing provided with a vane-free annular inlet passage opening into the impeller inlet, said casing having a by-pass therein the inlet of which opens into the impeller discharge passage and the outlet of which opens tangentially into said vane-free inlet passage at its outer periphery, the outlet of said by-pass pointing in the direction of rotation of the impeller whereby liquid entering the inlet passage from the by-pass will set up a vortex in the liquid as it passes inwardly through the vane-free passage to the suction of the impeller said vortex rotating in the direction of rotation of the impeller and increasing in velocity inversely as the distance from the axis thereby imparting rotation to the fluid prior to its entrance into the impeller in the same direction as the rotation of the impeller.
4. In a multi-stage centrifugal pump, a casing, stage impellers in said casing, said casing having inlet passages and discharge passages for each of said stage impellers, said casing provided with

a by-pass having its inlet opening into the discharge passage of one of said stage impellers subsequent to the first stage impeller and its outlet opening into the suction passage of the same impeller for returning part of the liquid pumped by the impeller back from its discharge to its suction the outlet of said by-pass being arranged whereby it enters said inlet passage tangentially thereof and pointing in the direction of rotation of the impeller whereby liquid entering the inlet passage from the by-pass will set up a rotation of the liquid in the inlet passage in the direction of rotation of the impeller the inlet passage leading to the by-passed stage impeller being vane-free, and direction vanes in the discharge passage of the impeller which discharges into the inlet passage of the by-passed impeller, said direction vanes acting to impart limited pre-whirl to the normal flow of liquid entering the inlet passage of the by-passed impeller.

5. In a multi-stage centrifugal pump, a casing, stage impellers in said casing, said casing having inlet passages and discharge passages for each of said stage impellers, said casing provided with a by-pass having its inlet opening into the discharge passage of one of said stage impellers subsequent to the first stage impeller and its outlet opening into the suction passage of the same impeller for returning part of the liquid pumped by the impeller back from its discharge to its suction, the inlet of said by-pass leading tangentially from the impeller discharge passage in the direction of flow therein and the outlet of said by-pass entering said inlet passage tangentially thereof and pointing in the direction of rotation of the impeller whereby liquid entering the inlet passage from the by-pass will set up a rotation of the liquid in the inlet passage in the direction of rotation of the impeller, the inlet passage leading to the by-passed stage impeller being vane-free, and direction vanes in the discharge passage of the impeller which discharges into the inlet passage of the by-passed impeller, said direction vanes acting substantially to remove pre-whirl from the normal flow of liquid entering the inlet passage of the by-passed impeller, and adjustable means for regulating the quantity of liquid flowing through said by-pass.

6. The method of regulating the head and capacity of a centrifugal machine such as a pump or compressor which comprises by-passing a controllable quantity of the handled fluid from a point of higher pressure back to the inlet of an impeller of the machine and introducing the stream of such returned liquid into the liquid flowing in normal flow to the impeller suction at a large radial distance from the axis compared with the impeller radius and tangentially into and inwardly through a vane-free passage in such manner as to set up a vortex in the entering fluid, the velocity of which vortex increases inversely as the distance from the axis and thereby imparts rotation to the fluid prior to its entrance into the impeller in the same direction as the rotation of the impeller.

7. In a centrifugal machine such as a pump or compressor, a casing, an impeller in said casing having an inlet and a radial outward flow passage, said casing having an annular vane-free passage which parallels the radial outward flow passage of the impeller, and means for by-passing a controllable quantity of the fluid handled by the machine from a point of higher pressure back to the inlet of said impeller, said means introduc-

ing the by-passed fluid tangentially into said annular vane-free passage at its outer periphery and in such manner as to create a converging vortex in the inlet of the impeller.

- 5 8. In a centrifugal machine such as a pump or compressor, a casing, an impeller in said casing having an inlet and a radial outward flow passage, said casing having an annular vane-free passage which parallels the radial outward flow passage of the impeller, and means for by-passing a controllable quantity of the fluid handled by the machine from a point of higher pressure back to the inlet of said impeller, said means arranged to discharge the fluid from the by-pass tangentially into said annular vane-free passage at its outer periphery in the direction of rotation of the impeller and tangentially of the fluid flow path to the impeller.
- 20 9. In a centrifugal machine such as a pump or compressor, a casing, an impeller in said casing having an inlet and a radial outward flow passage, said casing having an annular vane-free passage which parallels the radial outward flow passage of the impeller, and means for by-passing a controllable quantity of the fluid handled by the machine from a point of higher pressure back to the inlet of said impeller, said means arranged to discharge the fluid from the by-pass into said annular vane-free passage at its outer periphery in the direction of rotation of the impeller and tangentially of the fluid flow path of the impeller, and means for removing any pre-whirl from the normal flow of the fluid to the suction of the impeller.
- 35 10. In a centrifugal machine such as a pump or compressor, a casing, an impeller in said casing having an inlet and a radial outward flow passage, said casing having an annular vane-free passage which parallels the radial outward flow passage of the impeller, and means for by-passing a controllable quantity of the fluid handled by the machine from a point of higher pressure back to the inlet of said impeller, said means introducing the by-passed fluid into said annular vane-free passage at its outer periphery in such manner as to create a converging vortex in the inlet of the impeller, and means for removing any pre-whirl from the normal flow of fluid to the suction of said impeller.
- 40 50 11. The method of regulating the head and capacity of a centrifugal machine such as a pump or compressor which comprises by-passing a controllable quantity of the handled fluid from a point of higher pressure back to the inlet of an impeller of the machine and introducing the stream of such returned liquid into the liquid flowing in the normal flow path to the impeller suction at a large radial distance from the axis compared with the impeller radius and in a tangential direction so as to set up a vortex in the entering fluid, the velocity of which vortex increases inversely as the distance from the axis and thereby imparts rotation to the fluid prior to its entrance into the impeller in the same direction as the rotation of the impeller, and removing any pre-whirl from the liquid flowing in normal flow to the impeller suction prior to the mixing of the by-passed fluid therewith.
- 55 60 65 70 75 12. In a centrifugal pump, a casing, an impeller in said casing having an inlet and a discharge, said casing provided with a liquid inlet passage opening into the impeller inlet, a transition space in advance of said inlet passage and a by-pass having its inlet opening tangentially

into the impeller discharge and its outlet opening tangentially into said transition space, the outlet of said by-pass pointing in the direction of rotation of the impeller, whereby liquid entering the inlet from the by-pass will set up a rotating vortex of the liquid on the suction side of the impeller in the direction of rotation of the impeller so that the difference in moment of momentum and thereby the head produced by the impeller will be reduced, and a needle valve in said by-pass for regulating the quantity of liquid by-passed.

13. In a centrifugal pump, a casing, an impeller in said casing having an inlet and a discharge, said casing provided with a liquid inlet passage opening into the impeller inlet, a transition space in advance of said inlet passage and a by-pass having its inlet opening tangentially into the impeller discharge and its outlet opening tangentially into said transition space, the outlet of said by-pass pointing in the direction of rotation of the impeller, whereby liquid entering the inlet from the by-pass will set up a rotating vortex of the liquid on the suction side of the impeller in the direction of rotation of the impeller so that the difference in moment of momentum and thereby the head produced by the impeller will be reduced, and a needle valve in said by-pass for regulating the quantity of liquid by-passed, and pressure actuated means for operating said needle valve.

14. The method of regulating the head and ca-

pacity of a centrifugal machine such as a pump or compressor which comprises by-passing a controllable quantity of the handled fluid from a point of higher pressure back to the inlet of an impeller of the machine and introducing the by-passed fluid tangentially into and inwardly through a vane-free passage into the inlet of the impeller to produce a converging vortex in the inlet which co-operates with the outward whirling flow of the impeller for regulating the head and capacity of the machine.

15. In a centrifugal pump, a casing, an impeller in said casing having an inlet and a discharge, said casing provided with a vane-free inlet passage formed as a space of revolution opening into the impeller inlet, said casing having a by-pass therein the inlet of which opens into the impeller discharge and the outlet of which opens tangentially into said inlet passage at its outer periphery, the outlet of said by-pass pointing in the direction of rotation of the impeller whereby liquid entering the vane-free passage from the by-pass will set up a vortex in the liquid as it passes inwardly through the vane-free passage, which vortex rotates in the direction of rotation of the impeller and increases in velocity inversely as to the distance from the axis, a needle valve for controlling the quantity of liquid by-passed, and means actuated by pressure variations in the discharge of the pump for automatically adjusting said needle valve.

LEWIS F. MOODY.
